GAME APPARATUS

Oscar K. Fischer, Chicago, Ill., assignor of one-half to Phillip Fischer, Chicago, Ill.

Application January 25, 1935, Serial No. 3,377

6 Claims. (Cl. 273—121)

This invention relates to a game apparatus.

It is an object of this invention to provide an improved game apparatus which is relatively simple and inexpensive in construction and efficient in use.

Another object of the invention is to provide a game apparatus of the so-called pin and marble game or bagatelle type in which there is provided an inclined playing field or ball raceway and

means for automatically and simultaneously propelling a plurality or group of balls down said raceway toward the lower end thereof and against pins or other obstructions arranged thereon whereby the balls are caused to race down the

raceway and against the pins arranged thereon.

A further object of the present invention is to provide in a game apparatus, the combination of: a game apparatus comprising a cabinet, including an inclined playing board having ball exit openings therein; means for propelling balls one at a time onto the upper portion of said playing board so that they may gravitate thereover and enter into said exit openings; runways below said playing board and each having communication with a predetermined number of said exit openings; an inclined ball raceway below said playing board and having communication at its upper end with the lower ends of said runways; a barrier movably mounted in said cabinet between the upper end of said raceway and the lower ends of said runways and adapted to stop balls traveling down the latter toward said raceway; and means including an electromagnetic device actuated by balls entering said runways and coacting with said barrier to propel balls out of said runways down the said raceway.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a top plan view of a preferred form of the new game apparatus;

Fig. 2 is a longitudinal section of the same on line 2—2 in Fig. 1;

Fig. 3 is an enlarged fragmentary sectional detail view on line 3—3 in Fig. 1;

Fig. 4 is a fragmentary bottom plan view on line 4—4 in Fig. 3;

Fig. 5 is a perspective detail view, partly in section showing part of the resetting device for a ball-releasing trap door which is embodied in the present apparatus;

Fig. 6 is a fragmentary perspective detail view of the combination ball-obstructing barrier and ball propelling device embodied in the invention;

Fig. 7 is a fragmentary top plan view of the ball run-ways, on line 7—7 in Fig. 2;

Fig. 8 is a diagrammatic view of the electric circuit embodied in the invention; and

Fig. 9 is an end elevational view on line 9—9 in Fig. 8.

A preferred form of the new game apparatus 10 is shown in the drawings, is therein generally indicated at 10, and comprises a cabinet 11 which includes an inclined playing board 12 having ball exit openings 13 formed therein.

Arranged at one side of the playing board 12 is 15 a ramp or runway 14 and arranged at the lower end of the ramp 14 is a ball propelling device or plunger 15 by means of which balls may be propelled one at a time up the ramp 14 onto the upper portion of the inclined playing board 12 so 20 that they may enter into the ball exit openings 13.

Pivotaly mounted upon the playing board 12 in each ball exit opening 13, as at 16, is a trap door 17. Each of these trap doors or closure members 17 includes an arm 18 which projects into the corresponding exit opening 13 when the trap door is in open position, as in position "A", Fig. 3, and each of these trap doors 17 includes a closure plate 19 which is disposed in position to close the corresponding exit opening 13 when in closed position, as in position "B", Fig. 3.

Arranged in the cabinet 11 below the inclined playing board 12 is an inclined floor 20 and provided upon the upper portion of this inclined floor 20 are a plurality of parallel ball runways 21 each 35 having communication with a preselected number of the ball exit openings 13.

The major portion of the upper surface of the inclined floor 20 provides a ball raceway 22 which is disposed below the inclined floor 12 but is visible from above the same by reason of the fact that the inclined board 12 is provided with a cut-out portion 23 which is coincidental with the area of the raceway 22.

Provided upon the raceway 22 are a plurality 45 of pins 24 and arranged at the lower end of each runway 21 is a circuit-closing device in the form of an electrical contact 25, each of these contacts 25 providing a seat for a ball 26; spaced parallel rails 27 being provided on the inclined floor 50 20 at the mouths or lower ends of the runways 21 to separate or isolate the balls when the same are disposed upon the ball seats or contacts 25.

Extending transversely across the lower ends or mouths of the runways 21 is a ball-stopping 55

member or barrier 28 which is pivotally mounted at its ends, as at 29, in suitable supports 30 which, in turn, are mounted upon the inclined floor 20 as shown in Fig. 6.

5 The barrier or ball-stopping member 28 includes spaced parallel rails 31 and 32, and this barrier 28 is normally urged by a spring 33 into position, as shown in Fig. 6, to dispose the rail 32 in engagement with the upper surfaces of the 10 side rails 27 of the runways 21 while at the same time positioning the rail 31 sufficiently high above the upper surface of the inclined floor 20 so that balls traveling down the runways 21 may pass under the rail 31 and engage against the rail 32 15 of the barrier 28 and be held thereby upon the contacts or circuit-closing devices 25.

Each of the circuit-closing devices or movable contacts 25 is engageable, as shown in Fig. 3, with a relatively stationary contact 34, and these 20 circuit-closing devices 25—34 are arranged in an electric circuit 35, shown in Fig. 8. This circuit 35 includes an electromagnetic device 36 and a suitable source of electric current, such as a battery of dry cells 37, which may be arranged at 25 convenient points in the cabinet 11.

Carried by the ball-stopping member or barrier 28 is an arm 38 (Fig. 6), and engageable with this arm 38 is the plunger or armature 39 of the electromagnetic device 36.

30 Balls may be propelled one at a time, by the plunger 15, up the runway or ramp 14 onto the upper portion of the inclined playing board 12 so that they may enter into the ball exit openings 13, and upon passing through the latter pivot the trap doors 17 into closed position, as in position 35 "B", Fig. 3, whereupon the balls drop down into their respective runways 21 and are guided by the latter to the lower end portions of the runways 21 where they pass under the rail 31 of the 40 barrier 28 and engage against the rail 32 of the said barrier 28 by which they are thus stopped and held in position upon the ball seats or contacts 25.

The ball seats or contacts 25 are arranged in 45 a series circuit as shown in Fig. 8, so that in order to close this circuit it is necessary that a ball 26 be disposed in each of the runways 21 and upon each of the several ball seats or circuit-closing contacts 25.

50 When the foregoing condition is brought about by the player, that is, when there is a ball disposed upon each of the ball seats or contacts 25, which may be effected through the exercise of skill in directing the balls into the exit openings 55 13, then the electric circuit 35 is closed; whereupon the arm 39 of the solenoid 36 is projected into engagement with the arm 38 of the ball stop or barrier 28, thereby pivoting the barrier 28 in a counterclockwise direction, as seen in Fig. 6, or in a clockwise direction as seen in Fig. 8. This movement of the barrier 28 causes the rail 31 thereof to engage the balls 26 which are disposed on the contacts or ball seats 25, and at the same time raises the rail 32 of the barrier 28 up above the side rails 27 of the runways 21, thereby propelling the balls 26 out of the runways 21 and off the contacts or circuit-closing members or ball seats 25 and down over the inclined raceway 22, whereupon the balls may engage with the pin 24 and be deflected thereby from point to point as they travel down the raceway 22. The group of balls 26 in this way are caused to race down the raceway 22 and the player's interest is maintained in watching the relative or competitive movement 70 of the balls 26 down the raceway 22 to the lower

end thereof, whereupon the balls are directed by the angled side walls 40 of the raceway 22 into a relatively restricted runway 41 which is provided with a plurality of ball exit openings 42. These ball exit openings 42 are formed in the 5 inclined playing board 20 and arranged below the exit openings 41, but normally disposed out of registration with the same, and a plurality of ball exit openings 43 which are formed in a panel or gate 44 which is slidably mounted in the cabinet 11 below the inclined floor 21.

The ball releasing member or slide panel 44 carries a depending bracket 45 and the inner end of the coin slide 46 is engageable with the bracket 45 so as to move the slide panel 44 and 15 dispose the exit openings 43 therein in registration with the exit openings 42 at the start of each game, whereupon the balls disposed in the ball seats or exit openings 42 are discharged through the latter and the exit openings 43 onto 20 the inclined runway 47 by which the balls are conducted to a transverse runway 48 and are, in turn, guided by the latter into an elevating device (not shown) by which they may be elevated one at a time up into the ramp 14 in front of the 25 propelling device or plunger 15.

The circuit closing devices or contacts 25 are mounted upon a supporting base or gate 49 which is pivotally mounted at its ends, as at 50, (Fig. 5) in a cut-out opening 53 which is provided in the 30 inclined floor 20. Attached to and depending from the pivotal support or gate 49 is an arm 51 which is normally urged by a spring 52, into full line position, Fig. 3, so as to dispose the gate or support 49 in raised position in the cut-out opening 53 in the inclined floor 20 in which this gate or support 49 is pivotally mounted.

Attached to the slide member 44 is an arm 54 which is adapted to engage with the depending arm 51 when the member 44 is shifted (left to right, Fig. 3) by action of the coin slide 46, thereby pivoting the contact support or gate 49 into lowered or dotted line position, as in Fig. 3, so as to discharge from the support or gate 49 onto the inclined runway 47 any balls which may be disposed upon the ball seats 25 at the start of the playing operation. When the coin slide is released the slide member 44 is returned to its initial position (right to left, Fig. 3) by means of an arm 57 which is attached to and depends from 50 a slide plate 55 which is slidably mounted upon and below the inclined playing board 12 (Fig. 3); this arm 57 being engageable with a lateral extension 58 of the slide member 44, and as the engagement of the arm 57 with the extension 58 returns the slide member 44 to its initial position (right to left, Fig. 3) the spring 52 acts upon the arm 51 to pivot the gate 49 into closed position as in full lines, Fig. 3, the gate 49 being stopped in raised position by means of a stop 60 so that its upper surface is substantially flush with the surface of the inclined floor 20.

The slide plate 55 is provided with tongues 56 which are adapted to engage the arms 18 of the 65 trap doors 17 when the latter are in closed position, and the slide plate 55 is shifted (left to right, Fig. 3) by engagement of the lateral extension 58 of the slide member 44 with the depending arm 51 of the slide plate 55, so as to pivot the 70 trap doors 17 into open or upright position, as in position "A" in Fig. 3.

No claim is made in the present application to any invention in the trap doors 17 or slide plate 55 by which the same are reset into closed position 75

since these parts are not the invention of the present applicant.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

15. 1. In a game apparatus, the combination of: a cabinet including a member providing a ball-playing surface; a plurality of ball runways having communication with said ball playing surface; a member movably mounted in the said cabinet including a ball-propelling portion and including a ball-stopping or barrier portion normally disposed in the path of balls traveling along said runways toward said playing surface; and means actuated by balls held in the said ball runways by the said barrier portion of said second-named member for moving the said barrier portion of the latter out of engagement with the balls held thereby in said runways while at the same time moving the said ball-propelling portion of said second-named member into engagement with the said balls so as to propel the latter out of said runways onto the said playing surface.
2. In a game apparatus, the combination of: a cabinet including a member providing a ball-playing surface; a plurality of ball runways having communication with said ball playing surface; a member movably mounted in the said cabinet including a ball-propelling portion and including a ball-stopping or barrier portion normally disposed in the path of balls traveling along said runways toward said playing surface; and means including an electromagnetic device actuated by balls held in the said ball runways by the said barrier portion of said second-named member for moving the said barrier portion of the latter out of engagement with the balls held thereby in said runways while at the same time moving the said ball-propelling portion of said second-named member into engagement with the said balls so as to propel the latter out of said runways onto the said playing surface.
3. In a game apparatus, the combination of: a cabinet including a member providing a ball-playing surface having an opening formed therein; a member pivotally mounted in said opening; a plurality of ball runways arranged upon said playing surface and each having a portion extending over said pivotally mounted member; a member pivotally mounted in the said cabinet including a ball-propelling portion and including a barrier or ball-stopping portion normally disposed in the path of balls traveling along said runways; means normally urging the said second-named member into raised position against the attraction of gravity; means actuated by balls disposed upon said second-named member for moving the said third-named member in a direction to move the said barrier or ball-stopping portion thereof out of engagement with the balls held thereby in

the said runways while at the same time moving the said ball-propelling portion of the same into engagement with the said balls so as to propel the latter out of said runways; and means for moving the said second-named member into lowered position against the action of said urging means so as to discharge balls held thereby in said runways to a point below said playing surface.

4. In a game apparatus, the combination of: a cabinet including a member providing a ball-playing surface having an opening formed therein; a member pivotally mounted in said opening; a plurality of ball runways arranged upon said playing surface and each having a portion extending over said pivotally mounted member; a member pivotally mounted in the said cabinet including a ball-propelling portion and including a barrier or ball-stopping portion normally disposed in the path of balls traveling along said runways; means normally urging the said second-named member into raised position against the attraction of gravity; means including an electromagnetic device actuated by balls disposed upon said second-named member for moving the said third-named member in a direction to move the said barrier or ball-stopping portion thereof out of engagement with the said balls held thereby in the said runways while at the same time moving the said ball-propelling portion thereof into engagement with the said balls so as to propel the same out of said runways; and means for moving the said second-named member into lowered position against the action of said urging means so as to discharge balls held thereby in said runways to a point below said playing surface.

5. In a game apparatus, the combination of: a cabinet; a plurality of inclined ball runways in said cabinet; a barrier movably mounted in said cabinet and normally disposed in the path of balls traveling along said runways, and means including a device actuated by the conjoint action of a plurality of balls held by said barrier, one in each of said runways, for moving said barrier out of engagement with the said balls held thereby so as to release the said balls simultaneously and thus permit them to travel by gravity past said barrier along said runways.

6. In a game apparatus, the combination of: a cabinet including a member providing a ball-playing surface; a member movably mounted in said cabinet and including a barrier portion normally disposed in the path of balls traveling over said playing surface; said member including a ball-propelling portion movable into engagement with the said balls upon said playing surface by the said barrier portion of said member; and means including a device actuated by the conjoint action of a plurality of balls held or stopped upon the said playing surface by the said barrier portion of said member for moving the said member in such a manner as to move the said barrier portion thereof out of engagement with the said balls held thereby, while at the same time moving the said ball-propelling portion of the said member into engagement with the said balls thus released from engagement with the said barrier portion of said member, and thus propel the same over said playing surface.

OSCAR K. FISCHER.
